SORTING MACHINE

Eugene Amzi Ford, Scarsdale, N. Y., assignor to
 International Business Machines Corporation,
 New York, N. Y., a corporation of New York

Application March 11, 1938, Serial No. 195,240

7 Claims. (Cl. 209—110)

This invention relates to machines adapted for sorting record cards used in accounting systems.

The record cards represent data by means of 5 differentially located perforations therein, the value and character of the information conveyed by each perforation being dependent on its location on the card. The function of the sorting machine is to sense the perforations of a stack 10 of cards and thereby sort or classify them into groups as desired by the operator, to make available pertinent data which may then be computed and recorded.

The main object of the present invention is 15 to provide a mechanism adapted for a wide variety of sorting work. The sorting devices disclosed are designed to sort according to digit perforations in a single column, according to the length of a name or number represented by perforations, and according to multi-column selection 20 of a plural ordered number, all without changes other than the selective operation of switches and placement of plug wiring for securing the results desired.

25 An important object of the invention is the provision of means capable of sorting for a plural ordered number and at the same time sorting for digits in a column inside or outside the record area in which said number appears. For example, all records perforated to represent a plural ordered number such as 386 may be separated from the other records at the same time that digit sorting is carried on with relation to one order of the number. If then, the units order 30 controls digit sorting, a record representing 133 goes to the "3" pocket; record 389 goes to the "9" pocket; record 486 goes to the "6" pocket; and at the same time all multi-column selected records bearing the number 386 go to the "12" 35 pocket. In the same manner, groups of selected records may be sent to the "12" pocket at the same time that other records are sorted according to the digits represented thereon. For example, cards representing 5-9 may be grouped 40 while cards representing 1, 2, 3 or 4 may be sorted separately; or cards representing 400 to 599 may be grouped while records containing hundreds digits other than 4 or 5 may be sorted separately. In other modes of operation, digit 45 sorting and multiple column selection may each be performed alone, or both may be performed together with reference to different portions of the records.

It is another object of the invention to provide 50 improved devices for sorting according to the

length of a name or number. Notice may be drawn to the fact that a name increases in length to the right, while a number extends towards the left as it is made larger. The disclosed length sorting control devices may be connected to 5 sense any portion of the records and to sense length of data in that portion in either direction.

A feature of the invention is the provision of 10 a sensing brush for every column of the record cards and contact members extending from each brush adapted to receive two connections for control in digit or length sorting. A pair of thin plates are in contact with each insulated brush holder, and these plates are formed with two sets 15 of extensions arranged as knife switches receptive to one contact blade for digit sorting and another contact blade for control of length sorting.

Another object of this invention is the provision 20 of a movable column selector with a knife switch blade which may be brought into contact with any one of eighty brush switches, each of which relates to a column sensing brush for controlling sorting.

An object of the invention is the provision of 25 a multi-column numeral selection plate with a plurality of columns of switches, each switch operable to set up a sorting control digit in a related denominational order. Each switch is pivoted and fitted with a finger piece which may be rotated to establish an electrical connection.

Another feature of the present invention is the 30 novel construction of the sorting blade operating devices. The blades are mounted dependently so that the bottom blade may hold up all others, and any other blade when supported holds up all other blades above it, while the unsupported lower blades remain lowered to open a sorting 35 passage. Associated with each blade is a supporting member that may be latched in a raised position by a latch which is tripped by the armature of a sorting magnet. The magnets are selectively energized by the card sensing devices. The dependent nature of the sorting blade construction is utilized to obtain combined digit and multi-column selected sorting control. Then, even though the blade for a particular digit is lifted, if the predetermined multi-column number is sensed, the lowest blade (the 12 pocket 40 blade) is lifted and all other dependent blades, including the preselected digit blade, are held up while the card is directed into the 12 pocket.

Further objects of the instant invention reside 45 in any novel feature of construction or op-

eration or novel combination of parts present in the embodiment of the invention described and shown in the accompanying drawings whether within or without the scope of the appended 5 claims and irrespective of other specific statements as to the scope of the invention contained herein.

In the drawings:

Fig. 1 is a sectional elevation view of the card 10 feeding and sensing end of the sorting machine.

Fig. 2 shows a card perforated to represent short numbers and names.

Fig. 3 shows a card representing a long number and a long name.

15 Fig. 4 is a perspective view of the front ends of the sorting blades.

Fig. 5 is a plan view of the movable column selection contact frame and the length selection plugboard.

20 Fig. 6 is an elevation view of the card sensing brushes showing the knife switch construction of the column selector.

Fig. 7 is a plan view of a portion of the switch board containing the multi-column digit selection 25 switches.

Fig. 8 is a detailed view of one of the digit selection switches.

Fig. 9 is an elevation of a pair of the length sorting control relays.

30 Fig. 10 is a plan view of the unit containing the sorting control magnets and the mechanism controlled thereby to operate the sorting blades.

Fig. 11 is a sectional elevation view of the sorting control unit.

35 Fig. 12 is a wiring diagram of the wiring connections in the machine.

The perforated cards 8 and 8a shown in Figs. 2 and 3 are the kinds of records to be sorted by the machine of the present invention. In Fig. 2 40 it is seen that twelve index point positions are provided in each vertical column of the eighty columns of the record. The records are to be sorted according to the location of the perforations therein. For ordinary digit sorting, the index points of a certain column are sensed and the card is directed into one of thirteen sorting pockets according to the location of the perforation 45 in said column; the extra "reject" pocket is provided to receive unpunched cards.

50 When sorting according to the length of a name or number, the vertical location of the perforations in the columns is not a controlling factor; the control is then exercised according to the number of columns found with perforations 55 of any digital value. Cards with any number of columns punched, from zero to twelve columns, are sorted into thirteen pockets. It is noted that the number perforated on the card 8a of Fig. 3 is longer than the number 386 punched in 60 card 8 of Fig. 2, also that the direction in which the large number extends is towards the left. The perforations representing the long name on card 8a extend toward the right in the direction opposite to the extension of the large number. 65 The controls of the present machine are made flexible to be plugged to sense length of data in either direction.

70 Where it is known that a certain number appears a large number of times in a group of cards, time is saved by sorting the cards carrying said number into the "12" pocket at the same time that the other cards are sorted separately according to digits. For such multi-column or certain number selection, switches are provided to 75 set up the series of digits comprising the num-

ber. For example, in multi-column selection of cards such as card 8a (Fig. 3), seven switches are set to sense the perforations representing number 2657923 and control the direction of cards 8a into the "12" pocket.

5

Referring to Fig. 1, it may be pointed out that much of the framework and general operating controls disclosed therein are described in detail in Patent 1,969,362. The machine includes a base 1 supporting thirteen cards receiving pockets 3 separately identified and arranged as follows from left to right

R 9 8 7 6 5 4 3 2 1 0 11 12

All the numeral designated pockets are related 15 to the twelve index point positions in a column on the card. When the machine is set to sort the cards under control of a particular column, a perforation in one of the twelve positions in the column will cause that card to be sorted into the 20 corresponding pocket. A card having no perforation in the column controlling sorting will be fed to the R or reject pocket.

The machine is driven by an electric motor 25 which is connected to the main driving shaft 16. This shaft is connected to sets of card feeding rollers 17 and also to a shaft 18 on which is fixed a cam 19 adapted to move an arm 20 against the action of springs 21. The arm is pivoted at 22 and is connected at the upper end to a 30 plate 23 provided with a card picker 24. The cam 19 moves the picker toward the left and the spring 21, acting against the arm 20, moves the picker back toward the right. Each movement of the picker to the left causes the lowermost card 8 in the stack to be moved forward 35 into cooperation with the first set of feed rollers 17. These rollers then feed the card to the next set of rollers. As the card is being fed from the first to the second set of rollers, it 40 passes under a line of eighty sensing brushes 14, one for each column of index points on the record card. In passing from the second to the third set of rollers, the edge of the card encounters the right hand ends 5 of a plurality of guide blades 45 4 which are mounted across the tops of the pockets and serve to form paths to the separate pockets. The rollers continue to feed the card across the machine until it drops into one of the several sorting pockets 3.

50 The sensing brushes 14 (Fig. 1) are guided and separated by a notched insulation roller 29 above a contact roller 28 with which the brushes contact when perforations are sensed in the cards. Each brush 14 (Fig. 6) projects from a separate 55 holder 30 which is embedded in an insulation bar 31 attached to a rectangular supporting bar 32 which extends across the machine and is attached to the side frames 33 and 34. The holders are spaced at regular intervals corresponding to the 60 columnar arrangement of the index points on the cards.

Extending rearwardly from each holder 30 (Fig. 5) is a blade 35 which passes between the 65 flared ends 36 of a pair of contact strips 37 embedded in an insulation base plate 42. There are eighty such pairs of strips 37, one pair for each brush and brush holder, the purpose being to extend the area in which plug connections may 70 be made to the brushes. Blade 35 and ends 36 form a knife switch connection which is maintained as long as the strip plate 42 is held on the supporting bars 43 fixed in the side frames. This type of construction makes it easy to as- 75

semble and remove the strip extension unit because it is free of wire connections.

In addition to the flared ends 36, each pair of strips 37 is formed with two other sets of flared 5 knife switch extensions such as 38 and 39 to provide ready connections to the related brush. The second set of strips 37, Fig. 5, is provided with switch extensions 40 and 41 which are not aligned with the similar extensions 39 and 38 on 10 the first pair of strips. In Fig. 5 it is noted that the extensions 39 and 40 of alternate pairs of strips 37 are displaced so that the switches are arranged in a staggered formation. The other extensions 38 and 41 are also out of line as are 15 the others of the first six switches which are arranged in echelon. This is done to avoid contact between the flared ends of adjacent switches and to provide more room for plugging.

The switch extensions 38, 41, etc. arranged in 20 six rows (Figs. 1 and 5) are provided for making plug connections to the brushes for length and multi-column control of sorting. Above these switch extensions is fixed a cover 44 with a platform on which there are assembled rows 25 of insulation bushings 45 each formed with an opening 46 through which a plugging tip or blade 47 may be inserted and forced between the extensions 38 to establish electrical contact therewith. The plug wires 48 upon which the 30 tips 47 are fixed are connected to sorting control magnets when length sorting control is desired, and other connections therefrom to relays are made effective when multi-column sorting control is sought as explained more fully with 35 reference to the wiring diagram. Double bushings 45' may be provided to give access to multiple extensions 38 or 41 wherever needed.

The other extensions 39 and 40 are used for 40 making a single column selected connection for control of ordinary digit sorting. Cooperating with these staggered switch extensions 38 and 45 40 is a single column selection blade 49 (Figs. 1 and 6) which is movable to cooperate with any extension. In Fig. 1 it is seen that this 45 column blade 49 is wide enough to engage with one pair of either of the pairs of extensions 38 and 40. A contact bar 50 extends across the machine and is pivoted at 51 on the two side frames and urged to bear against blade 49 to 50 carry current therethrough regardless of the position in which the selection blade may be placed.

The selection blade 49, when being changed in 55 position from cooperation with one switch extension to another, must not only be moved across the machine but it must be raised first to break the knife switch connection, and then shifted to the new position, and finally lowered into contact. The blade is supported on a movable slide 60 25 which may be manipulated or automatically shifted across the machine.

Blade 49 (Figs. 1 and 6) is riveted to an insulation block 52 that is fastened to the slide 25 which is loosely mounted in the center of a shifting frame 53. This frame is cut out at the bottom (Fig. 1) to straddle a rectangular bar 54 fixed on the side frames. A hole is drilled horizontally through the upper part of frame 53 (Fig. 6) so that the frame may slide along, and 65 be guided by, a worm 26 which passes therethrough in extending across the machine. When observed from above, as in the plan view, Fig. 5, the frame 53 is seen to be in the form of an I with the slide 25 confined between the ends of 70 the frame. Viewing the slide 25 from the side 75

(Fig. 1), it is apparent that it is substantially in the shape of an inverted U, the sides of which slide up and down the reduced section of frame 53.

The slide 25 and attached blade 49 are normally forced down into a contact making position by means of a pair of compression springs 55 pressing between a ledge 56 on slide 25 and a shoulder inside a recess cut into frame 53. When so depressed, a toothed rack section 57 10 on slide 25 is engaged with the threads on the worm 26. At the same time a V shaped projection 58 on slide 25 is pressed down into an aligning notch 60 in an alignment bar 59 extending between the side frames. Worm 26 15 serves to move the slide across the machine, and bar 59 serves to prevent the lowering of blade 49 in any position other than the eighty switch closing positions wherein the blade is aligned with flared extensions 39 and 40. 20

Attached to the frame 53 is a pointer 61 which cooperates with a line of numerals (Fig. 5) on cover 44. These numerals are aligned with related brush and index point positions so that when the operator observes the position of the 25 pointer 61, he is able to determine the card column that is being analyzed for digit sorting control. The pointer is secured to the frame at both ends and formed with a U shaped bridge passing around the slide 25 to free it for vertical 30 movement.

Frame 53 and slide 25 may be shifted in either of two ways; by grasping a ring 62 on slide 25 and lifting the slide to disengage it from worm 26 and bar 59 when it is desired to shift the column selection unit through a wide range of adjustment across the sensing unit, or by turning a crank lever 27 attached to worm 26 for automatically shifting the selection blade when narrow variations in placement of one or more columns are to be made. 35

When ring 62 is grasped and lifted against the tension of springs 55, tooth section 57 is lifted out of cooperation with the threads on worm 26 and projection 58 is raised out of the 45 notches 60. Then frame 53 is free to be moved along bar 54 and worm 26 to any columnar position the operator desires. By watching the scale associated with pointer 61, the proper position may be found before releasing the ring so 50 that the slide 25 is pushed down by springs 55. Then blade 49 is forced into contact between a selected pair of extensions 39 or 40 as guided by projection 58.

Rotation of lever 27 and worm 26 in either direction also serves to shift the column selection unit. With this mode of control, however, the inverted U shaped path of travel of the unit is produced automatically, and the distance shifted is short, being from column to column, one column of movement for each revolution of arm 27. When rotated, the thread on worm 26 cooperates with the toothed section 57 to shift the entire unit. Worm 26 not only shifts the unit but it raises and lowers the unit so that blade 49 is 60 automatically withdrawn upward out of extension 40 before moving to the right or left. This is brought about by the vertical movement of the entire worm 26 in vertical slots in the main side frames, as caused by cams 63 on both ends of 70 the worm, cooperating with roller 64 fixed to the frames. A steep cam face on cam 63 cooperates with roller 64 as soon as arm 27 is turned, so that the worm is lifted before it has rotated an appreciable amount. The entire column selec- 75

tion unit is lifted therewith and then shifted as the turning worm acts on the teeth of section 57. At the end of the revolution, the steep sided groove in cam 63 again cooperates with roller 64 to suddenly lower the worm and the unit. Thus, blade 49 is thrust down between the knife switch extensions of another column. The worm construction and operation is described in greater detail in Patent 1,741,992.

10 Referring to Fig. 1, it is noted that a plurality of guide blades 4 are mounted across the tops of the several pockets and serve to form separate paths thereto. There are twelve such thin blades of varying lengths arranged in a compact pile shaped with pointed ends 5 at the common right end of the pile. The left end of the lowermost blade 4 is attached to and terminates at a bar 6 above the first or "12" pocket. A deflector 65 is formed on the blade to guide the 15 sorted cards down into the pocket 3. Bar 6 extends across the machine and is secured to the main side frames. The left end of the next blade above the lowermost is attached to, and terminates at, a bar 7 above the "11" pocket.

20 All the other blades 4 of progressively greater lengths are attached above related pockets in a similar fashion. A card fed from the stack 5 moves between upper and lower guide plates 9 and 10. Normally, all of the guide blades 4 are 25 held above the plane of the oncoming card 8 so that, unless they are lowered, the card will pass under all of the blades and drop into the "12" pocket. If the lowermost blade is lowered and all the other blades are held in the upper position, the card will pass between the two lowest 30 blades and be guided into the "11" pocket. The paths to all the other pockets are prepared in a similar way, by holding up the blade leading to the desired pocket, and all blades above it; and 35 at the same time lowering all blades below it. In Fig. 4 the dependent arrangement of the blades is clearly illustrated. There it is seen that if the "12" blade is held up, all the other blades are also raised because they depend on it.

40 And if, for example, the "7" blade is held up, the dependent "8" and "9" blades are also raised while all others fall. If all the blades are lowered, the card will pass above the uppermost one and below a strip 11 which together form a path 45 leading into the reject "R" pocket.

The pointed right end of each blade 4 (Fig. 4) tends to move downward, but is normally prevented from doing so by a supporting actuator or slide stem 12 which forms part of the 50 sorting control unit shown in Figs. 10 and 11. There it is seen that the twelve stems 12 extend down into the unit wherein they are selectively held up or allowed to fall under the control of sorting magnets SM which are in turn controlled by the perforations in the cards.

The sorting control unit, Fig. 1, is supported on a base plate 68 fastened to the main base 1 by standards 69. Side frames 70 and 71 (Figs. 10 and 11) and rear frame 72 provide support 55 for most of the devices in the unit. Six of the sorting magnets are mounted on a bracket 73 fastened to the frame 72, and the other six magnets are on a bracket 74 fastened to the plate 68. The magnets are divided into two groups 70 and staggered in location, Fig. 10, to provide larger coils than would be possible with all twelve magnets in a row.

The magnets SM control the release of a set of twelve latches 75, Fig. 11, mounted on a 75 common pivot 76. Each latch 75 is adapted to

pass under a block 77 on a related stem 12 to prevent the lowering of the stem. The magnets SM are each designed for the control of an associated latch. Six of the latches have straight vertical ends 78 descending for control by the lower group of magnets, while the other six alternate latches have bent ends 79 reaching to the right for control by the upper set of magnets. Springs 80 tend to rock the latches to pass the top ends under blocks 77, but the 10 latches are normally prevented from so moving because the ends 78 and 79 abut against armatures 81 and 82 associated with the magnets. However, when a control magnet such as SM1 is energized, the armature 82 is attracted and 15 rocked counterclockwise about the pivot 83, away from the stop rod 84 and end 79, to free the related latch 75 so that it may be positioned to hold up a stem 12.

The lower ends of the stems 12 slide freely 20 between a bar 87 and a rod 88 fastened in the side frames. Near the upper end, two shafts 89 and 90 guide the stems. Springs 91 tend to pull the stems down, but they are normally held up by a restoring member 92 which extends across 25 the unit underneath the releasing and restoring blocks 93 fastened to the stems.

Member 92 is lowered late in each cycle, after the card has been completely analyzed and after a latch 75 is tripped to hold up a selected stem 30 12. As member 92 descends, blocks 93 follow down, carrying the stems along therewith as urged by springs 91. Only those stems 12 with blocks 77 engaging the tops of tripped latches 75, will maintain the position shown in Fig. 11; all other stems are lowered and the blades 4, Fig. 4, resting on those stems will bend down at the pointed end to open a path under the raised blade 4 leading to the selected sorting pocket. A stop block 95 on stem 12 strikes the top of bar 87 when the stem is lowered, and thus serves to limit the downward movement of the stem.

The restoring member 92 is actuated by a cam 96 (Fig. 11) mounted on a shaft 13 carrying one of the card feed rollers 17. This shaft makes 45 one revolution in a counterclockwise direction during each cycle of operation of the machine. Cooperating with the cam is a follower arm 97 loosely fulcrumed on a shaft 98 which passes through the unit side frames 70 and 71. The 50 follower is adjustably secured to shaft 98 by means of a screw fastening 99 which attaches the arm to a member 100 carried on a hub 101 (Fig. 10) pinned to shaft 98. Member 100 is formed with a slot through which the screw 99 55 passes to make an adjustable connection between arm 97 and member 100 whereby arm 97 may be inclined at a desired angle with respect to the restoring member 92 which is also secured to the shaft 98.

Restoring shaft 98 turns in a pair of bushings 102, 103 fastened to the unit side frames by means of large hexagonal nuts 104, 105. The portion of the shaft between the side frames is cut to form a semi-circular cross-sectional area 65 against the flat edge of which, restoring member 92 is secured by screws 106. Follower arm 97 extends below the pivot and there carries a stud 107 to which is secured a spring 108 tending to rock it in a counterclockwise direction. This lower extension of follower 97 also acts as a limiting stop in cooperation with the end of an adjustable screw 109 extending from a block 110 fixed to the side frame 71.

Late in each sorting cycle, cam 96 presents a 75

- depression under the end of the follower arm 97, permitting this arm to rock in a counterclockwise direction as urged by spring 108. The attached shaft 98 carries restoring member 92 along therewith to lower it under the blocks 93 permitting these blocks and the attached stems 12 to descend, opening the sorting blades 4. After a card has entered between certain of the sorting blades and before the next card is sensed, a rising face 111 on cam 96 strikes the end of the follower 97 and rocks it positively in a clockwise direction to lift member 92 and carry along therewith the blocks 93 and the attached stems 12 in an upward direction.
- 15 Immediately after the leading edge of the card is projected between the pointed ends of sorting blades 4, the latches 75 are restored to allow all lifted stems 12 to descend. This restoring operation is actuated by means of a cam 112 (Fig. 20 1) attached to the outer end of shaft 13. Cooperating with the cam is an arm 113 attached to a shaft 114 which extends through bushings mounted in the unit side frames 70 and 71. A portion of the shaft 114 between the side frames 25 is cut in a semi-circular formation against the flat side of which is attached a restoring member 115 (Fig. 11) cooperating with the top ends of the latches 75. A spring 116 (Fig. 1) attached to arm 113 tends to rock the shaft 114 in a clockwise direction to place the end of arm 113 in cooperation with the surface of cam 112. An adjustable screw 117 limits the clockwise motion of the arm 113 and shaft 114.
- 30 Late in each sorting cycle, directly after the leading edge of the card enters between the blades, a projection on cam 112 strikes the end of arm 113 and rocks it in a counterclockwise direction, rocking shaft 114 and member 115 (Fig. 11) along therewith to contact the sides of the upper end of latches 75, rocking them in a clockwise direction. The ends 78, 79 of latches 75 are then restored beyond the ends of the armatures 81 and 82. Frames 118 and 119 are provided in cooperation with the ends of latches and the sides of the armatures to insure the restoration of these two parts to the normal abutting relationship. The frames overcome the pull of any residual magnetism which may tend to hold the armatures away from ends 78, 79 and adjustable stops 84 and 85.
- 35 Another control unit is provided similar in appearance to the unit containing the sorting magnets. This unit (Fig. 9) contains a set of twelve relays for controlling the operation of twelve contacts RC0—RC12 which are used when sorting is controlled for selecting certain multi-denominational number cards. The base of this unit is an extension of the base 68 under the sorting unit. Upon the base is supported a pair 40 of side frames 121, 122 parallel with the side frames 70 and 71 of the other unit. The twelve relays R0—R12 are mounted in two groups in staggered formation similar to the mounting of the sorting magnets. The armatures 123 and 45 124 of these relays cooperate with the ends 125 and 126 of latches 127 pivoted on rod 128. These latches are similar in construction to the latches 75 described with respect to Fig. 11. However, in connection with the relays these latches 127 are used for another purpose. Attached to the lower end of each of the twelve latches 127 is an insulation stud 129 cooperating with the outer blade of a pair of contact blades comprising one of the sets of contacts RC0—RC12. The blades 50 75 of these contacts are mounted on an insulation block 130 attached to the base 68 and held between the side frames 121 and 122. Although only six of the ends 125 and latches 127 cooperate with armatures 123, six other such extensions are provided on the other six latches in order that a mounting place may be provided for the twelve insulation studs 129. When any of the relays are energized, the related armature is attracted and the associated latch 127 is released and permitted to rock in a counterclockwise direction under the urging of spring 131. This motion carries the stud 129 away from the associated contact blades, allowing the related pairs of contacts to close.
- 55 The contacts and operating latches 127 are restored by means of shaft 114 which extends from the sorting magnet unit over through the relay unit. Between the side frames of the relay unit, shaft 114 is cut to form a flat surface against which is fixed a restoring member 132 positioned to cooperate with the ends of latches 127. When this shaft is rocked in a counterclockwise direction at the end of a sorting cycle, the ends 125 and 126 of the latches are forced below the outer ends of the armatures so that the armatures may again resume their normal abutting relationship with the latches. At the same time studs 129 are forced to the left (Fig. 9) to open the contacts RC0—RC12.
- 60 A switchboard is provided for setting up a series of digit switches for selecting a predetermined number to control the multi-column card sorting selection. This switchboard also contains means for setting controls to sort according to the length of a name or number sensed on record cards. Referring to Fig. 7, it is seen that the lower part of the switchboard comprises a sheet of insulation 133 in which there is embedded a series of ten contact points 134 arranged in a zig-zag formation. Directly opposite each of the points 134 and on a horizontal line therewith is an associated contact point 135. The points 135 are joined by a wire or bar 136. Two other similar sets of points 137, 138, 139 and 140 are independent of the connection between points 134 and 135.
- 65 Directly above plate 133 is mounted the top frame 141 of the board. This frame is spaced from the lower plate by sets of washers 143 which encircle screws 142 holding the upper and lower parts of the switchboard together. The top frame 141 is cut out with a series of staggered rows of holes through which protrude the manipulative circuit closing switch members 144. Each of these knob members may be made of insulation material and slotted to receive a metallic contact bridge or bar 145 (Fig. 8) adapted to bridge the space between the points 134, 135 on the lower plate 133. These lower contact points 144 are formed with concave surfaces to receive a pair of points 146, 147 extending down from the contact member 145. A compression spring 148, confined within an opening cut inside member 144, bears against a shoulder on the contact bridge 145 and tends to press it down into cooperation with the points 134, 135. A pin 149 extends through the lower part of member 144 and through a vertical slot cut in contact member 145 to guide and limit the vertical motion of the metallic contact member within the body of the knob 144. The upper part of each manipulative knob 144 is flattened on two sides so that the part may be grasped by the fingers and twisted to turn the points 146, 147 in and out of co-

operation with the contact points 134 and 135. When the flattened end of a knob is in a vertical position (Fig. 7), the points of the related digit switch are open. When the flattened portion is in a horizontal position, such as the position of the "3" switch at the left in Fig. 7, this switch serves to form a connection between the selected one of the points 134 and the point 135 connected in series with other points 135. Fig. 8 also illustrates the position of one of the switches when in contact-making condition. In Fig. 7 it is noted that the ten switches related to a single series of digits 0 to 9 are found in two rows arranged in a staggered formation. This is done to make the board compact by saving the space that would otherwise be occupied, should ten switches be placed in a straight row.

Above each set of ten digit switches are mounted two other switches for length and multi-column control associated with the same column. These special switches are constructed the same as the digit switches, the only difference being that they are wired to secure special control which is described more fully hereinafter with reference to the wiring diagram. The top multi-column selection switch may be turned horizontally to close the space between contacts 137 and 138. The other length control switch may be twisted to bridge the space between points 139 and 140.

As shown in Fig. 7, the digit switches are set to select the number 386. This would serve to control the direction of any card perforated to represent 386 into the "12" pocket while other cards would be directed into other digit representing pockets.

Referring to the wiring diagram in Fig. 12, it is noted that closure of the main switch S prepares the sorting devices for operation. Then, if the start key is depressed, a circuit is established through the starting relay RA. The circuit may be followed from one main line 201, through stop key contacts SP, contacts ST, relay RA, relay RB and over to the other main line 200. Relay RB immediately closes associated contacts 151 which complete a circuit through the sorting operating motor 15. The sorter then operates to feed the cards. As soon as the cards are fed, they operate the card lever 216 to close contacts 219 in shunt around the start contacts ST, so that the start key may be released and the machine will continue to run as long as cards pass the lever.

In preparing the devices for ordinary digit control of sorting (i. e., where a single column is sensed, and cards with a "9" perforation in that column are sent into the "9" pocket, cards with "8" perforations are directed to the "8" pocket, etc.) the switches SW1 and SW2 are closed as shown, and the column selection blade 49 is positioned to contact with the knife switch blades 39 or 40 of the desired column sensing brush 14. Then the cards are fed and sensed, and the sorting magnets SM are selectively energized according to the position of a perforation in a column of the card. Assuming that a "5" perforation is sensed to control sorting, the following circuit would then be established through the hole in the card: starting at line 200, the impulse passes through contact brush 153, contact roll 28, then to brush 14 through the hole in the card, knife switch 39, contact blade 49, common contact bale 50, wire 154, switch SW1, a selector brush 208, 76 the "5" segment 204 which passes brush 208 at

the instant, a common contact ring 203, wire 155, sorting magnet SM5, distributor wire 156, the "5" distributor segment 157, brush 159, wire 160, and switch SW2 to line 201. In the same way, any of the other sorting magnets may be energized through one of the twelve lines 156 when the related distributor segment 157 is touched by brush 159 at the same time that the associated selector-segment 204 is touched by brush 208 at the time when sensing brush 14 passes through a perforation. The energized sorting magnet (Fig. 11) then acts to trip latch 75 to lock a stem 12 which holds up all blades 4 above the one leading to the desired pocket.

The operating shafts 13 of the selector and distributor (Fig. 12) coincide with the shaft 13 (Fig. 1) of the card feed, so that synchronism is maintained between the appearance of the various index points at the three sensing controls. The selector (Fig. 12) is constructed as set forth in detail in Patent 1,741,985. Each of the segments 204 may be separately disconnected from the common contact ring 203 or engaged therewith as desired. This selective digit control makes it possible to avoid the sorting of certain digit representing cards, or the direction of certain cards to the reject pocket. When sorting for the ten digits only, the "11" and "12" segments 204 may be disconnected as shown.

The controls are adjusted for sorting according to the length of a name or number by plugging the tips 47 into the desired sensing sockets 38, shifting switch SW1 to touch terminal 162, opening switch SW2, and closing all switches 145 (Figs. 7 and 8) in line with the designation "Length" on switchboard 141 to bridge all contact spots 139 and 140, Fig. 12. The tip 47 at the left with a wire 48' leading to the sorting magnet SM9 may be plugged in at the left when name lengths such as those at the right in Figs. 2 and 3 are being considered. Then all one letter name cards are sent to the "9" pocket, all two letter cards are directed into the "8" pocket, etc. Since numbers extend to the left in length, Figs. 2 and 3, it is advisable to take the tip 47 connected with wire 48' and bring it over to the right of the number sensing brushes 14 so that it is connected with the units order brush. Then all the other plug wires are connected from right to left which is the reverse of the order in which they are shown in Fig. 12, and the reverse of the order maintained for name length sorting. With such number length connections established, all single denominational number cards will go to the "9" pocket, all cards with numbers of two denominations will go to the "8" pocket, etc.

It may be pointed out that, when sorting according to length, the placement of the perforations in the columns is of no moment, the main consideration being, how many columns are perforated in any position.

Assuming a condition in length sorting, when a card with a four letter name is sensed, the following circuit may be traced; from line 200, through brush 153, roller 28, four brushes 14 at the left, sockets 38, tips 47 and four wires 48, spots 140, four switches 145, spots 139, four wires 163 leading to the four sorting magnets SM6, SM7, SM8 and SM9, wire 155, selector ring 203, segments 204 and brush 208, switch SW1 and terminal 162 to line 201. Although all four magnets trip the associated latches 75, Fig. 11, and lock up the related stems 12, the card will be directed to the "6" pocket because of the four blades 4 (Fig. 4) that are held up by the stems

12, the lowest blade, which is the one that opens a path to a pocket, is the "6" blade. In this fashion, length sorting is controlled by the energized magnet relating to the last letter of a name, or the highest denomination of a number.

Preparations are made to secure multi-column selection control of sorting by plugging a plurality of tips 47 to the sensing brushes 14 of the orders selected for exercising control. At the same time, the switch SW2 is closed and certain of the switches 144, Fig. 7, are turned to the horizontal position to set up a number, or numbers, to control sorting. All the length switches 144 are turned off, as shown in Fig. 7, and the top row 15 of "Multi col" switches to the right of the selected number representing switches, are turned on.

As shown in Figs. 7 and 12, a setting is made to sort cards perforated with the number 386 such as the card 8 in Fig. 2. If such perforations are encountered by the three plugged sensing brushes 14, a circuit is completed to the sorting magnet SM12. Although in the example shown, the switches 145 at the left are set to represent the number 386 with the plug wire 48' extending to the brush sensing the highest order denomination column on the card, it is possible to set such a multi-column selection member at any other part of the switchboard, providing that the "Multi col" switches are closed in the top row in all columns not used for number setting, and providing that the correct plug wires 48 are connected to the several brushes 14 which are effective because they cooperate with the perforated columns of the cards. For purposes of illustration it may be assumed that the number 386 is set up at the extreme left end of the switchboard. The circuit through the highest order multi-column relay R8 may be followed from line 200 through brush 153, roll 28, brush 14 sensing a "3" perforation, socket 38, tip 47, wire 48', relay magnet R9, contact bar 136, switch bridge 145 in the "3" position, point 134 on the "3" wire 156, "3" segment 157 on the distributor, brush 159, wire 160, and switch SW2 to line 201. Relay R9, Fig. 9, then attracts the armature 123, and releases the latch 127 to permit the related contacts RC9 to close. The other two relays R8 and R7 (Fig. 12) are energized in a similar way when they sense the "8" and "6" perforations, respectively, and thereby act to close contacts RC8 and RC7. The closure of all three contacts RC9, RC8 and RC7 is an indication that the number perforations in the card agree with the number set up on the switchboard, and the sorting magnet SM12 is energized to open a path to the "12" pocket. Magnet SM12 is made effective by a circuit including line 200, wire 165, contacts RC9, RC8 and RC7, switch bar 145 closed across points 137 and 138 to shunt contacts RC8, eight similarly closed switch bars 145 arranged in shunt around the unused relay contacts, wire 166, magnet SM12, wire 156, "12" distributor segment 157, brush 159, wire 160, switch SW2 and line 201. Although other sorting magnets may be energized by an early completion of the series circuit through the relay contacts, this does not affect the correct multi-column sorting operation, because when the magnet SM12 is energized it latches the stem 12, Fig. 4, which holds up the "12" blade 4 underlying all other blades. In effect, the "12" magnet SM12 neutralizes the action of the other magnets so that the cards with the selected multi-column number representations are directed into the "12" pocket.

The aforementioned neutralizing action of the "12" magnet makes it possible to perform digit and multi-column sorting at the same time. All cards may be sorted according to the digits in a selected column, at the same time that certain 5 cards bearing a predetermined multi-denominational number are directed into the "12" pocket.

In order to control for combined digit and multi-column sorting, the machine is set up as explained in connection with the selection of cards punched with the number 386, and in addition thereto the switch SW1 (Fig. 12) is closed to line 154 and column selector blade 49 is moved to contact with a desired sensing brush 14. The digit control column selected may be aside from the 15 multi-column perforations as the single column at the left in Fig. 2, or it may be any of the columns containing the multi-column designations. Assuming that the digit column selected is the units order column of the perforated area 20 at the center of card 8, Fig. 2, i. e. the column containing a "6" perforation, a digit sorting control circuit may be traced as follows: from line 200 through brush 153, roll 28, the third brush 14 from the left passing through a "6" perforation, socket 39, blade 49, common contactor 50, wire 154, switch SW1, brush 208, "6" segment 204, ring 203, wire 155, magnet SM6, wire 156, "6" distributor segment 157, brush 159, wire 160, and switch SW2 to line 201. Magnet SM6 then trips 30 the associated latch 75, Fig. 11, to lock up a stem 12 to prepare a path to the "6" pocket. However, at the same time that magnet SM6 is energized through the "6" perforation, relay R7 is also energized to close contacts RC1 and prepare part 35 of the multi-column series connections to the "12" pocket. Whether the card goes to the digit selected "6" pocket or the multi-column selected "12" pocket depends on the agreement of the other perforations in the card with the setting 40 on the switchboard. If the card agrees with the setting, then the magnet SM12 is energized as explained hereinbefore and the "6" pocket selection is overcome by the "12" pocket selection and the card goes to the end pocket. However, should 45 the card disagree in any column with the setting of the multi-column switches, then the magnet SM12 is not energized and the digit sorting selection prevails, the card going to the "6" pocket.

While there is disclosed the features of the invention as applied to a single modification it will be understood that various omissions and substitutions and changes in the form and details of the device illustrated, and in its operation may be made by those skilled in the art without departing from the spirit of the invention. It is the intention, therefore, to be limited only as indicated by the scope of the following claims.

What is claimed is:

1. In a machine for sorting records having index point indicia in several columns, each column having a plurality of index point positions, means for sensing said columns of indicia, a plurality of circuits and relays, one for each column sensing means, a switchboard with sets of contact knobs, 60 one set for each circuit and relay, each of said sets having a common contact bar and a plurality of individual contact points, one for each index point, said knobs being adjustable to connect certain points to the bars, an impulse distributor for said circuits, a sorting magnet, and a series of relay contacts arranged in series with said magnet and closed by said relays when the record indicia agrees with the data set up by the knobs. 75

2. In a machine for sorting records having indicia at index points in several columns, each column having a plurality of index point positions, a sorting control magnet, contacts connected in series with said magnet, means for shunting certain of said contacts, adjustable index point representing means associated with each of said contacts for setting up control data, means for sensing the index points of each column of indicia on a record, means under control of said adjustable means and said sensing means for operating related contacts when there is an agreement, and means under control of said magnet when energized by the closure of all contacts other than the shunted contacts for sorting the records with indicia agreeing with the set control data.

3. In a machine for sorting records with multi-denominational data represented by columns of digit indicia, a plurality of sensing means for sensing the columns of indicia, ten sorting pockets relating to the different digital indicia in a column, an extra sorting pocket for receiving records with a selected multi-denominational number, a series of magnets, means under control of said magnets for opening paths to said ten pockets, an extra magnet, means under control of said extra magnet which is energized for closing the paths to said ten pockets and opening a path to said extra pocket, all of said path opening and closing means being located at a common path selecting station directly beyond the sensing means, means for controlling the selective energization of said ten magnets under control of a selected one of said sensing means, means for setting up a multi-denominational number, means for connecting a plurality of column sensing means to said setting means and to said extra magnet to control the energization thereof when the data on any record agrees therewith, whereby digital and multi-columnar control of sorting takes place simultaneously, the records with multi-denominational numbers agreeing with the number set up, all being directed into said extra pocket, while all other records are sorted digitally into said ten sorting pockets.

4. In a machine for sorting records with columns of indicia differentially placed at index points in the columns, a set of sensing brushes, one for each column, a series of sorting pockets, a series of sorting control magnets, an impulse selector connected to said magnets and effective at index point positions in the cycle, means for selectively connecting said selector to one of said sensing brushes, means under control of said magnets for opening a path to one of said pockets according to the indicia sensed, an impulse distributor, parallel lines between said magnets and said distributor, said lines corresponding to the index points of the indicia, a series of relays, means for connecting each of said relays to a separate sensing brush, multi-column control switches for connecting each of said relays to one of parallel lines, a special sorting pocket, a magnet and means controlled thereby for opening a

path to said special pocket, contacts in series with said magnet and operated by said relays when the sensed indicia in a plurality of columns correspond to the setting of the switches on the parallel lines. 5

5. A machine for sorting statistical records comprising an analyzing device including a row of analyzing elements each adapted to traverse one of the columns of the records to successively sense the index point positions to detect name or number designations placed in any of the columns, sorting mechanism including sorter control elements adapted to selectively control sorting operations of said mechanism, means controlled by the analyzing elements for operating one or more of the control elements in accordance with the number of designated columns traversed by the analyzing device, and adjustable connections between said analyzing elements and said sorter control elements for selectively associating any of the control elements with analyzing elements traversing the columns at the right of the sensed columns or at the left of the sensed columns, whereby lengths of name data from left to right may be sensed, and lengths of number data from right to left may also be sensed.

6. In a machine for sorting records into a plurality of pockets according to the length and multi-columnar characteristics of data appearing thereon as indicia in a plurality of columns, means for sensing a plurality of the columns of indicia on the records, a series of sorting control magnets, electrical controls for causing said magnets to respond according to the length of data on the records, other electrical controls including means for setting up multi-column data for causing said magnets to respond according to the comparison of the sensed data with the data set up, means for connecting either of the electrical controls to said sensing means, means under control of said first mentioned electrical controls and said magnets for sorting the records into different pockets according to the length of data thereon, and means under control of said other electrical controls and said magnets for sorting records with data agreeing with said set up data into one of said pockets. 40 45

7. In a machine for sorting records according to digital and multi-columnar characteristics of data represented thereon by indicia in a plurality of columns, a series of record receiving stations, a single line of indicia sensing brushes, one of which may be common to control for digit and multi-column selection, means cooperating with said brushes for selecting records with predetermined multi-column characteristics and directing them to one of said receiving stations, means cooperating with said common sensing brush for controlling the selective distribution of the records, other than those having predetermined multi-column characteristics, among the remaining receiving stations according to the digital value of the indicia sensed by said brush. 50 55 60
